UNITED STATES PATENT OFFICE.

JOHN T. LANCASTER, OF HAVERHILL, MASSACHUSETTS, ASSIGNOR TO UNITED SHOE MACHINERY CORPORATION, OF PATERSON, NEW JERSEY, A CORPORATION OF NEW JERSEY.

PULLING-OVER MACHINE.

1,396,131.

Specification of Letters Patent.

Patented Nov. 8, 1921.

Application filed February 16, 1918, Serial No. 217,573. Renewed April 14, 1920. Serial No. 373,954.

To all whom it may concern:

Be it known that I, JOHN T. LANCASTER, a citizen of the United States, residing at Haverhill, in the county of Essex and State 5 of Massachusetts, have invented certain Improvements in Pulling-Over Machines, of which the following description, in connection with the accompanying drawings, is a specification, like reference characters on the 10 drawings indicating like parts in the several figures.

This invention relates to pulling-over machines and particularly to means for controlling the upper pulling mechanism of such 15 machines.

It has been proposed heretofore to provide in pulling-over machines, in addition to mechanism for initially pulling the upper, auxiliary power driven mechanism under 20 manual control for use in moving one or more of the upper pulling grippers subsequently to the initial pull, either in a direction to subject the upper to an additional tension or in a direction to relax the tension. 25 Mechanism by the use of which such supplemental movements of the grippers may be effected is shown and described, for example, in United States Letters Patent No. 1,333,536 granted on March 9, 1920, upon 30 an application filed by me and Eli Brothers as joint inventors. An important object of this invention is to provide means of simple and improved construction for controlling more effectually than heretofore the upper pulling mechanism of machines of the 35 above described and other types in order to facilitate such operation of the mechanism as to produce the precise results desired, and to guard against breakage of parts or 40 other undesirable consequences through operation of the upper pulling mechanism at the wrong time, or through other conditions such as might cause interference between such mechanism and other portions of the 45 machine.

For the accomplishment of the above and other objects the invention provides among its more important features, novel means for controlling the transmission of power to a

gripper or grippers by manually controlled 50 gripper operating mechanism and also novel means for insuring such control of a gripper as to permit it to be returned to its idle position with other portions of the machine.

These and other features of the invention, 55 including novel means whereby manual control of gripper operating mechanism to produce precise and accurate results in the tensioning of the upper is facilitated, together with certain details of construction and 60 combinations of parts, will now be described with reference to the accompanying drawings, which show one embodiment of the invention, and will be pointed out in the claims. 65

In the drawings,

Figure 1 is a side elevation of a pulling-over machine in which the invention is embodied, and

Fig. 2 is an enlarged perspective view of 70 a portion of the mechanism on one side of the machine for imparting supplemental movements to one of the side grippers, and the manual controlling means therefor.

The illustrative machine is similar in its 75 general organization to the machine shown in the patent hereinbefore referred to, and only such portions of the mechanism as it is necessary to refer to for an understanding of the present invention will be described 80 herein in detail.

The machine comprises the usual side grippers 2 connected to updraw levers 4 pivoted at 6 to the frame of the machine and operated in the usual manner by a cam 85 8 on a cam shaft 10 through connections comprising a slide 12 and rods 14 projecting upwardly from the slide, the rods being surrounded by springs 16 which bear at their upper ends on nuts 18 on the rods and are 90 arranged with their lower ends in position to impart movement to the rear end portions of the levers 4 when the slide is moved downward to compress the springs 16. After the slide 12 has been thus operated to 95 impart the first updraw movement to the side grippers, the machine comes to rest in the usual manner with the upper under ten-

sion in order to permit the work to be inspected and the grippers to be moved if necessary for the purpose of adjusting the position of the upper upon the last or of changing the tension applied to the upper.

In addition to the means above described for imparting a pulling movement to the side grippers, the machine is provided with power operated mechanism, similar to that shown in the patent referred to, which may be rendered effective by manual control to impart a further upper tensioning movement to the side grippers or, if desired, to relax in a greater or less degree the tension at one or both sides of the upper. This mechanism comprises separate connections between the power shaft 20 and each of the side grippers, together with separate controlling means for each gripper operating mechanism to enable the operator to cause either or both of the side grippers to move in the direction and to the extent desired. Since these connections and the controlling means therefor are duplicates of each other, only the mechanism for effecting and controlling the movement of the gripper at one side of the machine is shown and will be described herein in detail.

The shaft 20 carries a constantly driven gear 22 which drives a pinion 24 on a shaft 26, this shaft carrying a worm 28 which is arranged to drive a worm gear 30 fast on a vertical shaft 32. The shaft 32 carries a worm 34 by which it continually drives a worm gear 36 which is fast on a horizontal shaft 38 mounted to turn in bearings formed in a bracket secured to the side of the machine head. Splined on the shaft 38 and movable endwise thereon is a clutch member 40 provided on its respective end faces with teeth 42 and 44 arranged to engage alternately with similar teeth 46 and 48 formed on the end faces of beveled gears 50 and 52 which are mounted to turn loosely on the shaft 38. The teeth on the clutch member 40 and on the beveled gears are so formed with reference to the direction of movement of the member 40 as to remain in engagement until a substantial resistance is encountered, whereupon the teeth may slip in such manner as to produce a series of rapidly repeated short pulling impulses, but this particular arrangement of the teeth is not essential as far as the features of this invention are concerned. The clutch member 40 is provided with a circumferential groove in which are received blocks 54 carried by a forked projection on a hand lever 56 which is fulcrumed on the bracket at 58 and extends downwardly and forwardly toward the front of the machine where its end is inturned to provide a handle 60 in such position that the operator as he stands in normal working relation to the machine is enabled

to manipulate it while watching the progress 65 of the pulling action upon the upper. By raising the handle 60 the clutch member 40 is moved rearwardly along the shaft 38 to cause the teeth 42 to engage the teeth 46 and thereby impart turning movement to 70 the gear 50, while by lowering the handle the clutch member is moved in the opposite direction to cause the gear 52 to be driven.

The gears 50 and 52 are constantly in mesh with a beveled gear 62 fast on a vertical 75 shaft 64 which is mounted to turn in bearings in the bracket and the upper end of which is formed as a screw 66. The screw 66 is threaded in a sleeve 68 which is rigidly attached to and projects forwardly from a 80 slide 70 vertically movable in a guide 72 and provided with rearwardly projecting ears 74 and 76 between which is confined the end of a stud 78 extending outwardly from the rear end of the updraw lever 4.

In the operation of the machine comprising the construction thus far described, the usual machine clutch is actuated to cause a partial rotation of the cam shaft 10 and thereby to impart an initial pull to the 90 upper at the sides and the toe of the last, whereupon the machine comes to rest with the upper at the sides of the last under tension in proportion to the degree of compression of the springs 16. These springs 95 may be light enough to cause the upper simply to be gripped and straightened out upon the last, or they may be set to such a tension as to produce a pull as much stronger as may be desired. While the machine is at rest at the end of this initial movement, the auxiliary side gripper operating means may be rendered effective by the manipulation of the handles 60. In consequence of movement of these handles either 100 together or separately in one direction or the other, an additional pulling movement of such extent as may be desired may be imparted to either or both of the side grippers, or one or both of the grippers may be 110 moved in a direction to relax in a greater or less degree the tension of the upper effected by the initial movement of the levers 4. Upon relative movement of the handles 60, moreover, the upper may, if desired, be adjusted transversely of the last. 115

The machine includes means whereby the side grippers may be locked against retractive movement from the position to which they are moved in the initial operation of 120 the machine and also to cause them to retain the tension of the upper effected by the supplemental pulling movement. To this end, the front beveled gear 52 has rigid therewith ratchet wheels 80 and 82 provided with oppositely directed teeth with which coöperate pawls 84 and 86 pivoted on a stud 88. A spring 90 tends to move both 125

pawls in such direction as to cause them to engage the teeth of their respective ratchet wheels. On the outer ends of these pawls are mounted rolls 92 and 94 and between 5 these rolls is positioned a lengthwise movable rod 96 arranged to slide in bearings in the bracket upon which the shaft 38 is mounted. The rod 96 is provided with a recess for the reception of an upward extension 10 from the clutch controlling fork and is thus moved lengthwise in unison with the movement of the clutch member 40 by means of the hand lever 56. The rod 96 is provided with depressions 100 and 102 which 15 are arranged to coöperate respectively with the rolls 92 and 94 on the pawls, and with an intermediate portion of the full diameter between the two depressions which engages both rolls to position the pawls out of engagement 20 with the ratchet wheels when the clutch member 40 is in neutral position. When the rod 96 is moved toward the front of the machine by a depression of the hand lever 56, the roll 94 of the pawl 86 will be received within the depression 102 and thus 25 the spring 90 will be permitted to position the pawl 86 in engagement with the ratchet wheel 82 in such manner as to hold the side gripper in the position to which it has been 30 moved in the initial operation of the machine and also to retain whatever additional tension may be effected by the upward movement of the gripper by reason of the connection of the clutch member 40 to the gear 52 35 effected by the further depression of the hand lever 56. In the meantime the pawl 84 will continue to be positioned out of engagement with the ratchet wheel 80. If the hand lever 56 is uplifted to connect the 40 clutch member 40 with the gear 50 for moving the gripper in such direction as to relax the tension of the upper, the roll 92 will be caused to enter the depression 100 and permit the pawl 84 to engage the ratchet wheel 45 80 and thus retain the gripper in such position as it may be caused to assume upon a relaxation of the tension, the pawl 86 meanwhile being held by means of the rod 96 out of engagement with the ratchet wheel 82. 50 The depressions 100 and 102 are somewhat elongated in order to permit either pawl to engage its ratchet wheel before the teeth of the clutch member 40 have engaged the teeth of the respective gear 50 or 52, thus 55 affording provision for limited movement of the hand lever 56 to cause the gripper to be operated through the respective gear or to come to rest while the pawl remains in co-operative relation to its ratchet wheel. By 60 such limited movement of the lever 56 the operator is permitted to cause a plurality of movements to be imparted to the gripper at will while he observes the effect upon the upper stock, the gripper being retained meanwhile against movement in the opposite direction by the operation of the pawl and ratchet mechanism. 65

On the upper side of the controlling rod 96 is a notch in which is received the wedge-shaped end of a spring plunger 104 to retain the rod normally in a position in which the clutch member 40 is inoperative to transmit movement to either of the gears 50 or 52 and both pawls are held out of engagement with their ratchet wheels, the retention 70 of the pawls and the clutch member normally in such neutral position being further insured by spring plungers 105 arranged to engage a stud 107 projecting from a downwardly extending portion of the lever 56. 75 The shape of the notch and of the plunger 104, however, is such as to afford only a yielding resistance to movement of the rod 96, thus permitting the operator to manipulate the lever 56 when he so desires, the 80 notch and the plunger affording, moreover, an indication of the neutral position of the parts of the controlling mechanism. On either side of the notch in which the plunger 104 is received, the rod 96 is provided with 85 a slot 106 arranged to receive the end of the plunger 104 when the rod 96 is moved from its central or neutral position in one direction or the other. The slots 106 are suitably elongated to correspond to such 90 movement of the rod 96 as takes place during a movement of the lever 56 to connect the clutch member 40 to the teeth of the gear 50 or 52 or to disconnect it therefrom while the pawl 84 or 86 remains in engagement 95 with its ratchet wheel. The plunger 104 by engaging the rod at one end of the slot 106 will thus oppose a yielding resistance to continued movement of the rod in the same direction after disconnecting the member 40 from the immediately adjacent teeth 100 46 or 48 and will thereby afford the operator an indication of the extent of movement 105 of the lever 56 which is permissible for disconnecting the clutch member from the teeth 110 of the gear without disconnecting the locking pawl. Between the limits of movement of the rod thus determined by one end of the slot 106 and by the clutch teeth the plunger 104 will oppose no resistance to the free 115 manipulation of the controlling mechanism. The construction thus facilitates precise and accurate control and enables the operator to cause movements of the precise extent desired to be imparted to the gripper in succession without danger of retraction of the gripper from the position to which it may have been already moved by the operation of the hand controlled mechanism. 120

Although the springs 16 are of sufficient 125 strength usually to retain the side updraw levers substantially in such position as they may assume by reason of a supplemental

pulling movement effected by the mechanism hereinbefore described, it is preferable that the pawl 86 remain in effective engagement with its ratchet wheel 82 to retain the tension of the upper at least until such time as the grippers are moved inwardly to draw the margin of the upper over the bottom of the last in the usual manner in the final stage of the cycle of operations of the machine. In order to permit this it is necessary to keep the hand lever 56 depressed sufficiently to permit the pawl 86 to remain in engagement with the ratchet wheel 82 until after the machine clutch has been tripped to cause the overlaying and fastening of the upper to be effected. The resistance to movement of the rod 96 effected by the engagement of the plunger 104 with the rod at one end of the slot 106 is depended upon to retain the parts of the controlling mechanism in this position while permitting the operator to release the handle 60. It is important, however, in order to avoid breakage of any of the parts, such, for example, as the pawl or the slide 70, that the pawl be disengaged from the ratchet wheel before the parts of the machine are returned to their initial positions subsequent to the release of the upper by the grippers. In order to insure such release of the pawl, the rod 96 is provided with a recess 108 having upper edges sloping lengthwise of the rod, and arranged for engagement with the rod in this recess is a wedge-shaped dog 110 carried by a bar 112 which is operated at suitable times to cause the dog to be withdrawn from the recess and thus permit the operation of the manual controlling means or to enter the recess and thereby either return or insure the return of the rod and the parts connected therewith to their neutral or inoperative positions. Conveniently the rod 112 is carried by a slide 114 with which the machines of the illustrative type are provided for the purpose of oscillating the tack pot of the machine through connections with a rod 116 extending upwardly from the slide, the slide being moved upwardly in the first stage of the cycle of operations, during which the initial pulling movement of the grippers is effected, by means of an eccentric 118 on the cam shaft 10, and moved downwardly in the final stage of the cycle of operations during which the margin of the upper is drawn over the bottom of the last and fastened. It will be evident, therefore, that when the machine is at rest prior to its operation upon a shoe, the dog 110 will be positioned within the recess 108 and by locking the rod 96 will thus not only cause the pawls 84 and 86 to remain out of engagement with their ratchet wheels, but will also prevent such manipulation of the hand lever 56 as to cause power to be transmitted to either

of the gears 50 or 52. Effective insurance is thus afforded against accidental manipulation of the lever 56 at the wrong time with consequent danger of breakage. In the initial stage of the cycle of operations the dog 110 is withdrawn to release the rod 96 and thus leaves the mechanism free for manipulation by the operator during the time when the machine is at rest with the upper under the initial tension. In the final stage of the cycle of operations and prior to any such movement of the parts as might tend to cause breakage, the dog is again moved downwardly and by engagement with one of the sloping faces of the recess 108, in case the rod 96 is still positioned to permit one of the pawls to engage its ratchet wheel, imparts such movement to the rod as to disengage the pawl, the downward movement of the dog in any event serving to insure that the parts of the controlling mechanism shall be in their inoperative positions and to lock the parts in such positions until their subsequent release during the operation of the machine upon another shoe.

The dog 110 is rigid with a rod 120 which is adjustable vertically in the end of the bar 112 and is provided with a slot in which is received a flange 122 on an adjusting screw 124 which may be manipulated to raise or lower the rod 120 relatively to the supporting bar. It will be evident that by the use of this adjusting mechanism the dog 110 may be accurately positioned to cause it to lock or to unlock the rod 96 at precisely the time desired, the dog and the recess 108 being so formed relatively as to permit the dog to have a greater or less extent of lost motion while still positioned in the recess.

While the invention is herein illustrated in its application to a machine of the type disclosed in the prior patent mentioned, it will be understood that in many of its aspects the invention is not limited to machines of that particular type.

Having described the invention, what I claim as new and desire to secure by Letters Patent of the United States is:

1. In a pulling-over machine, the combination with a gripper and means for operating the gripper to cause it to pull an upper and to come to rest while holding the upper under tension, of power operated means for imparting subsequent movement to the gripper of variable extent as determined by the operator and in a direction to relax the tension of the upper, manual means for controlling the operation of said power operated means, and means for locking said manual means against operative movement in a direction for relaxing the tension until after the machine has been started for effecting said first mentioned pulling movement of the gripper.

2. In a pulling-over machine, the combination with a gripper and means for operating the gripper to cause it to pull an upper and to come to rest while holding the upper under tension, of power operated means for imparting subsequent movement to the gripper of variable extent as determined by the operator and in a direction to relax the tension of the upper, manual means for controlling the operation of said power operated means, means for normally locking said manual means against operative movement in a direction for relaxing the tension, and power operated means for unlocking said manual means after the machine has been started for effecting said first mentioned pulling movement of the gripper.

3. In a pulling-over machine, the combination with a gripper and means for operating the gripper to cause it to pull an upper and to come to rest while holding the upper under tension, of power operated means for subsequently moving the gripper either to increase or to relax the tension of the upper, manual means movable in opposite directions to initiate the operation of said power operated means for increasing and relaxing the tension respectively, and means for locking said manual means against movement in either direction until after the machine has been started for effecting said first mentioned pulling movement of the gripper.

4. In a pulling-over machine, the combination with a gripper and means for operating the gripper to cause it to pull an upper and to come to rest while holding the upper under tension, of power operated means for subsequently moving the gripper either to increase or to relax the tension of the upper, manual means movable in opposite directions to initiate the operation of said power operated means for increasing and relaxing the tension respectively, means for normally locking said manual means against movement in either direction, and means automatically operative to unlock said manual means after the machine has been started for effecting said first mentioned pulling movement of the gripper.

5. In a pulling-over machine, the combination with a gripper and means for operating the gripper to cause it to pull an upper and to come to rest while holding the upper under tension, of power operated means for imparting a supplemental pulling movement to the gripper, manual means for initiating the operation of said power operated means, means for locking the gripper with the upper under tension at the end of said supplemental movement, and mechanism for operating said locking means subsequently to unlock the gripper, said mechanism being constructed and arranged to lock said manual

means in position to prevent the operation 65 of said supplemental pulling means until after the machine has been started for effecting said first mentioned pulling movement of the gripper on another shoe.

6. In a pulling-over machine, the combination with a gripper and means for operating the gripper to cause it to pull an upper and to come to rest while holding the upper under tension, of power operated means for imparting a supplemental pulling movement 75 to the gripper, manual means for initiating the operation of said power operated means, means for locking the gripper with the upper under tension at the end of said supplemental movement, and a single means 80 for operating said locking means subsequently to unlock the gripper and for locking said manual means in an inoperative position to prevent the operation of said supplemental pulling means until after the 85 machine has been started for effecting said first mentioned pulling movement of the gripper on another shoe.

7. In a pulling-over machine, the combination with a gripper, of power operated 90 means for imparting an upper pulling movement to the gripper, manual means for initiating the operation of said power operated means, and means for locking said manual means normally against operative 95 movement comprising a member arranged for movement in unison with the movement of the manual means, said member having a recess therein, and a locking member arranged to enter said recess.

8. In a pulling-over machine, the combination with a gripper, of power operated means for imparting an upper pulling movement to the gripper, manual means for initiating the operation of said power operated means, a member movable in unison with the movement of said manual means, said member having a recess therein, a locking member arranged to enter said recess, and power operated means for withdrawing the locking member from said recess.

9. In a pulling-over machine the combination with a gripper, of power operated means for imparting movement to the gripper either to pull an upper or to relax the tension of the upper, manual means comprising a clutch member movable in opposite directions to initiate the operation of said power operated means for increasing and 115 relaxing the tension respectively, a rod connected to the clutch member for movement lengthwise in unison with said member, and means for locking said rod normally against movement in either direction.

10. In a pulling-over machine, the combination with a gripper, of power operated means for imparting an upper pulling move-

ment to the gripper, manual means for initiating the operation of said power operated means, a rod movable lengthwise in unison with the movement of said manual means, 5 and power operated means arranged to act through said rod to insure the return of said manual means to an inoperative position.

11. In a pulling-over machine, the combination with a gripper, of power operated 10 means for moving the gripper to pull an upper including a clutch member movable into or out of position to transmit movement to the gripper, manual means for moving said clutch member, means for locking the 15 gripper with the upper under tension, a member for controlling said locking means, mechanism arranged to act through said member to insure the subsequent unlocking of the gripper, and a connection between 20 said controlling member and the clutch member for controlling the position of the clutch member.

12. In a pulling-over machine, the combination with a gripper, of power operated 25 means for moving the gripper to pull an upper including a clutch member movable into or out of position to transmit movement to the gripper, manual means for moving said clutch member, pawl and ratchet 30 mechanism for locking the gripper with the upper under tension, means for controlling said pawl and ratchet mechanism to cause the gripper to be locked or unlocked comprising a lengthwise movable rod, means arranged 35 to act through said rod to insure the subsequent unlocking of the gripper, and additional means comprising a connection between the rod and the clutch member to insure that the clutch member shall be located 40 in an inoperative position when the gripper is unlocked.

13. In a pulling-over machine, the combination with a gripper, of power operated means for moving the gripper to pull an upper, manual means for initiating the operation 45 of said power operated means including a clutch member movable into or out of position to transmit movement to the gripper, a controlling member movable in unison with said clutch member, said controlling member having a recess therein, a power operated slide, and a locking member carried by said slide and movable into and out of said recess respectively at different times in 50 the cycle of operations of the machine.

14. In a pulling-over machine, the combination with a gripper, of a power shaft, means for operating the gripper through the movement of said shaft, manual means for locking the gripper against retractive movement, a member for operating said locking means to unlock the gripper, and means for transmitting operative movement from the power shaft to said member.

15. In a pulling-over machine, the combination with a gripper, of power driven operating mechanism, manual controlling means for rendering said mechanism effective or ineffective to impart movement to the gripper, a locking device arranged to be controlled by said manual means to render the device effective or ineffective to prevent retraction of the gripper, said manual means being arranged with freedom for unobstructed limited movement to connect the power mechanism to the gripper or to disconnect it therefrom while the locking device remains operative to hold the gripper against retraction, and means affording the operator an indication of the extent of such limited movement of the controlling means. 65 70 75 80

16. In a pulling-over machine, the combination with a gripper, of power driven operating mechanism, manual controlling means for rendering said mechanism effective or ineffective to impart movement to the gripper, a locking device arranged to be controlled by said manual means to render the device effective or ineffective to prevent retraction of the gripper, said manual means being arranged with freedom for unobstructed limited movement to connect the power mechanism to the gripper or to disconnect it therefrom while the locking device remains operative to hold the gripper against retraction, and means for yieldingly opposing further movement of the controlling means at the end of said limited movement in a direction to disconnect the power mechanism from the gripper. 85 90 95 100

17. In a pulling-over machine, the combination with a gripper, of power driven operating mechanism, manual controlling means for rendering said mechanism effective or ineffective to impart movement to the gripper, a locking device arranged to be controlled by said manual means to render the device effective or ineffective to prevent retraction of the gripper, said manual means being constructed and arranged for limited movement to connect the power mechanism to the gripper or to disconnect it therefrom while the locking device remains operative to hold the gripper against retraction, the machine including a member movable in unison with said manual means and having an elongated slot therein, and a dog arranged for yielding engagement with the member in said slot to afford the operator an indication of the extent of said limited movement of the controlling means. 105 110 115 120

18. In an upper pulling machine, the combination with an upper pulling gripper, of power operated means for imparting to said gripper movement either in a direction to pull an upper or in a direction to relax tension applied to the upper, manual controlling means operative by movements in op-

posite directions respectively to initiate power operation of the gripper to pull or to relax the tension, and mechanism normally operative to lock said controlling means against movement in either direction.

19. In an upper pulling machine, the combination with an upper pulling gripper, of power operated means for imparting to said 10 gripper movement either in a direction to pull an upper or in a direction to relax ten-

sion applied to the upper, manual controlling means movable in opposite directions respectively to cause the gripper to pull or to relax the tension, and mechanism automatically operative in the return of the power driven parts of the machine to starting position to lock said controlling means against movement in either direction. 15

In testimony whereof I have signed my 20 name to this specification.

JOHN T. LANCASTER.
